Carlos P. Griffin

ATTORNEY.

UNITED STATES PATENT OFFICE.

FRANK J. MIRGON, OF SAN FRANCISCO, CALIFORNIA.

RAZOR-HONE HOLDER.

Application filed January 26, 1925. Serial No. 4,804.

This invention relates to a razor hone holder and its object is to simplify the construction so as to produce a device which will be easily made and reasonably sold.

- 5 Another object of the invention is to produce a hone holder which is capable of being adjusted to any desired position for use and secured in that position upon a base which will hold it firmly.
- 10 Another object of the invention is to so form the base that it will hold the cup for securing the standard ball securely thereto, and to provide means whereby the base will carry a rubber washer to prevent the mar-
- 15 ring of furniture.

Other objects of the invention will appear as the description proceeds.

An embodiment of the invention is shown in the accompanying drawings in which the 20 same reference numeral is applied to the same portion throughout, but I am aware that there may be modifications thereof.

Figure 1 is a side elevation of the complete holder.

25 Figure 2 is a view of the holder looking at right angles to Figure 1.

Figure 3 is a plan view of the holder.

Figure 4 is a side elevation of the movable side of the holder showing a portion of the 30 standard to which the main holder is secured.

Figure 5 is a bottom plan view of the base; and

35 Figure 6 is a vertical sectional view of the standard.

The holder comprises a spun base 1, slightly raised at the center and provided with an inturned edge 2 to hold a flat soft rubber ring 3; the inturned edge being bent down 40 upon the edge of the said ring to secure it in place at the center of the base. It has a depression to receive the partly spherical shell 4, which shell has tabs 5 and 6 by which it is secured to the base through slots 5' and 45 6'. This shell also has ears 7 and 8 extending laterally therefrom, through which a bolt

9 with a wing nut 10 thereon passes to tighten or loosen the shell upon the spherical bottom 11 of the standard 12. The standard 12 is cast hollow and has a flat extension 13 and 14 at each end of the top to receive rivets 15 and 16 to secure the hone support 17 in place. The hone support is turned up at one edge as indicated at 18 to hold the hone and it is slotted at 19 to receive the plate 20, 50 forming the opposite side of the hone support, and which acts as a clamp to push the hone against the side 18. This plate 20 is notched at 21, 22 to hold it steady with respect to the support 17 and it is bent into 55 a U shape at 23 to give it a strong connection with the slidable bolt 24 to which it is secured by means of the screw 25. The bolt 24 passes through a hole in the standard 12 and there is a knurled nut 26 to 60 tighten the clamp against the hone 27.

In operation, the hone is placed on the hone support 17; the knurled nut 26 is then tightened to bring the plate 20 against the hone, whereupon the head 11 may be shifted 65 to any position the barber desires to place the hone in for convenient use.

What I claim is as follows, but modifications may be made in carrying out the invention shown in the drawings and in the 70 above particularly described form thereof, 75 within the purview of the claim herein:

A razor hone holder comprising hone holding means mounted on a spherical member, a base having a raised central portion, a 80 depression in said central portion adapted to receive said spherical member, a split partly spherical shell, ears on the free ends of said shell, said ears having a bolt and wingnut, and tabs on the bottom portion of said shell 85 adapted to engage slots in said raised portion of the base.

In testimony whereof I have hereunto set my hand this 15th day of January A. D. 1925.

FRANK J. MIRGON.
